CLAIM

Dec. 26, 2007 (JP) 2007-035551

(51) **LOC (9) Cl.** 18-02

The ornamental design for an ink tank for printer, as shown and described.

(52) **U.S. Cl.** D18/56

DESCRIPTION

(58) **Field of Classification Search** D18/14,
D18/18, 43, 50, 56-59, 99; 347/29, 30, 32,
347/33, 50, 62, 86-87; D9/417, 521, 533,
D9/569, 573

FIG. 1 is the front view of an ink tank for printer showing our new design;

See application file for complete search history.

FIG. 2 is a rear view thereof;

(56) **References Cited**

FIG. 3 is a top plan view thereof;

U.S. PATENT DOCUMENTS

FIG. 4 is a bottom plan view thereof;
